CARTRIDGE FOR CIGARETTE LIGHTER

Shirley McLarty, Dallas, Tex., assignor, by mesne assignments, to American Lighter Corporation, Fort Worth, Tex., a corporation of Texas

Substituted for abandoned design application Ser. No. 80,032, May 18, 1964. This application July 12, 1966, Ser. No. 4,079

Term of patent 14 years

(Cl. D48—27)

FIG. 1

FIG. 3

FIG. 2

FIG. 4

FIGURE 1 is a top plan view of the cartridge for cigarette lighter that incorporates the design of this invention;

FIGURE 2 is a side elevational view of the cartridge of FIGURE 1;

FIGURE 3 is an end elevational view, the opposite end being identical; and

FIGURE 4 is a side elevational view of the opposite side from that shown in FIGURE 2.

The bottom of the cartridge shown in FIGURES 1-4, is plain, and is identical in peripheral outline to FIGURE 1.

I claim:

The ornamental design for a cartridge for cigarette lighter, as shown and described.
